CONVECTION FLUID HEAT EXCHANGE UNIT WITH INTEGRAL SOOT BLOWERS

Paul M. Brister, Madison, and John C. Singleton, Jr., Watchung, N. J., assignors to The Babcock & Wilcox Company, New York, N. Y., a corporation of New Jersey

Application December 11, 1952, Serial No. 325,328

1 Claim. (Cl. 122—392)

This invention relates to gas heated fluid heat exchange units of the convection type.

More specifically the invention is concerned with the provision of a permanent or fixed type of soot blower as an integral part of a vapor generating unit involving a bank of vapor generating tubes heated by high temperature heating gases. The purpose of the soot blower is to promote cleanliness of the vapor generating tube surfaces subject to heating gas contact. Such gases generally have suspended solids therein, and in the operation of the unit some of these solids are deposited on the tubes. Such deposits decrease the heat transfer rates from the heating gases to the vaporizable liquid within the tubes. The invention provides a fixed soot blower operable to remove such deposits by the periodic operation of high pressure fluid jets directed against the tube surfaces which have had such solids deposited thereon. The jets are directed through nozzles or jet structures leading from a tube disposed in proximity to the main bank of convection tubes and disposed in the same gas flow zone. When the soot blower jets are operative the soot blower tube is protected against destructive heating effects of the gases by the cooling of metal by the soot blowing fluid, but as this fluid flows only periodically, the soot blower tube needs other thermal protection during the periods of inoperation of the soot blower jets. The invention provides such protection by enclosing the soot blower tube within an outer tube connected into the same fluid circulation system as that in which the main convection heating tubes are connected. Thus, for example, a vapor generator having a bank of upright vapor generating tubes heated by high temperature gases has one or more of the tubes enclosing a soot blower tube. The inner and outer tubes are connected by a multiplicity of jet structures welded to the tubes and directed radially toward the remaining, and adjacent tubes. The soot blower tube is thus maintained at a temperature of the order of the temperature of the vaporizable fluid even when the soot blower is inoperative. This reduces thermally created stresses in the inner and outer tubes and in their welded connections which also unite the soot blower jet structures to them.

The invention, in a more specific sense, involves such fluid heat exchange soot blower improvements in a unit operating at such high gas pressures that the entire convection heat exchange components must be enclosed within a pressure vessel. This is an arrangement which would practically exclude the use of retractible soot blowers.

In the pertinent unit, oxygen and methane are introduced into a reaction chamber under pressures in the range of 250-350 p. s. i. a., and in such proportions that their reaction results in heating gases of a temperature of the order of 2500° F. These gases are directed over the convection heat absorbing surfaces presented by upright banks of spaced vapor generating tubes. The upper ends of these tubes are connected with a liquid and vapor drum arranged exteriorly of the tube enclosing pressure

2

vessel, and the lower ends of the vapor generating tubes communicate with the liquid space of that drum by downcomer connections extending through the pressure vessel wall. These connections may include lower drums or headers circumferentially arranged within the pressure vessel and having the lower ends of different banks of the vapor generating tubes directly communicating therewith. Similarly arranged upper headers or drums may have the upper ends of the vapor generating tubes directly connected thereto within the pressure vessel. The high gas temperatures involved emphasize the need of thermal protection for the fixed soot blower tubes, a plurality of which are provided for each bank of vapor generating tubes.

15 When the pertinent unit involves a multiplicity of recurrent transverse gas passes over each bank of tubes, a corresponding multiplicity of transverse gas pass baffles are provided, and the soot blower jets are therefore preferably arranged in vertically spaced groups disposed at positions vertically spaced from the levels of the baffles with each transverse gas pass having its own series or group of soot blowers arranged for optimum cleaning of the tube portions within that gas pass.

20 For the purpose of compliance with the pertinent statutory requirements, the invention is concisely set forth in the appended claim, but for a better understanding of the invention, its characteristics and results, reference should be had to the accompanying description of a preferred embodiment illustrated in the accompanying drawings:

In the drawings:

Fig. 1 is a partial sectional elevation through the heat exchange unit involving convection heated tube bundles for vapor generation;

25 Fig. 2 is a sectional elevation of one of the tube bundles incorporating the illustrative soot blower constructions;

Fig. 3 is a partial horizontal section on the line 3—3 of Fig. 1;

30 Fig. 4 is partly an elevation and partly a sectional elevation of one of the soot blower constructions employed with each of the tube bundles of the Fig. 1 unit;

Fig. 5 is a vertical section through one of the soot blower constructions, on an enlarged scale;

35 Fig. 6 is a partial elevation of one of the soot blower constructions showing a group of the soot blower jet structures;

Fig. 7 is a transverse section on the line 7—7 of Fig. 6 showing the relationship of the soot blower jet structures to the inner soot blower tube and its enclosing vapor generating tube which is one of the tubes of a tube bundle;

40 Fig. 8 is a transverse section illustrating the annular and concentric relationship of a soot blower tube and its enclosing tube taken on the line 8—8 of Fig. 5;

Fig. 9 is a detail view partly in elevation and partly in vertical section of the lower part of one of the soot blower structures 68; and

45 Fig. 10 is a detail transverse section on the line 10—10 of Fig. 9.

The heat exchange unit of Fig. 1 involves a pressure vessel 19 in the lower part of which there is a furnace, or gaseous reaction chamber 12 having high temperature refractory walls 14 and 16 and a refractory roof 18. In one example of this unit, methane is burned in an atmosphere of oxygen, producing high temperature gases which pass recurrently transversely of the upright vapor generating tubes of the tube bundles. Each tube bundle connects a lower header or drum 20 to an upper header or drum 22, the vapor generated in the tube elements collecting in the upper header 22 and passing through the vapor discharge tube 24 to an external vapor and liquid

drum (not shown) which is connected to the upper part of the discharge tube 24 by a series of circulators 26.

There are series of transverse baffles which cause the heating gases to pass recurrently transversely of the tubes of each tube bundle. One series of these baffles includes the removable central baffles 28-31 removably disposed within the annular arrangement of tube bundles, and vertically spaced as indicated in Fig. 1. Another series of baffles is indicated by the baffles 34-36 extending from the outer parts of the baffles 28-31 and partially through the tube bundles.

Interposed relative to the baffles 34-36 are baffles 38-41 which extend partially through the tube bundles from the outer wall of the gas space. The lower header or drum 20 of each tube bundle is supplied with the vaporizable liquid by downcomers 44 which are indicated as passing through the upper part of the pressure vessel 10, at 45. These downcomers preferably communicate with the liquid space of an external vapor and liquid drum.

After leaving the upper parts of the tube bundles is indicated in Fig. 3, with tapered refractory baffles 50 closing the spaces between successive tube bundles. Between the downcomers 44 at the rear of the tube bundles and the wall of the pressure vessel 10, there are vapor generating wall cooling tubes 52 having space closing heat resisting material 54 therebetween. These tubes are connected into a fluid circulation system by appropriate connections including upper headers 55 and circulator tubes 56 extending upwardly from the headers. These circulator tubes exit through the upright wall of the pressure vessel at positions indicated at 58 and 60, and, to minimize thermally created stresses the circulators have helically disposed portions 62 interposed relative to the headers 55 and positions 58 and 60. The upper ends of the circulators may be connected to the external vapor and liquid drum and the lower ends of the wall tubes appropriately connected to the liquid space of the vapor and liquid drum.

Disposed centrally of each tube bundle and at a position close to the downcomers 44 is a soot blower structure 64, and a similar structure is disposed at each inner corner of the tube bundle at the positions indicated at 66 and 68 in Fig. 3. The soot blower structure 64 as shown at the right hand part of Fig. 2 includes an inner soot blower tube 70, concentrically fixed within an outer tube 72 by spacers 74-76 (Fig. 8) and the soot blower jet structures such as 77 and 78. These jet structures include short tubular sections extending through openings in the outer tube 72 and expanded therein or welded thereto, for pressure tightness. The inner end of each jet structure is welded to the inner tube 70 as indicated at 80, a small diameter opening 82 through the wall of the tube 70 providing for the flow of high pressure steam or other fluid through the jet structure. Preferably, the openings 82 are formed by drilling the inner tube after the jet structures are welded in their operative positions.

The lower end of each outer tube such as 72 is connected to the lower drum 20 by a tubular element 84, and the upper end of the outer tube 72 is similarly in communication with the drum 22 through a tubular element 86, these elements being connected in pressure tight relationship.

Fig. 6 shows one group of the soot blower jet structures such as 77 and 78, six jets being shown in this group. Such groups are disposed at the positions A, B, C, D, E, F and G along the soot blower structure 64 so as to effectively remove solids from the parts of the tube bundles disposed between the successive baffles such as 36-41.

The jets of the soot blower structure 64 are directed at different radial positions into the associated tube bundle as indicated by the arrows 90-92 in Fig. 3. The soot blower structures 66 and 68 toward the inner parts 5 of the tube bundles are constructed similarly to the manner above described, each having an outer tube such as 94 or 96 with an inner tube 98 connected to a source of high pressure fluid such as the vapor in the external vapor and liquid drum. The groups of soot blower jet structures for the soot blower structure 68 are disposed at positions such as indicated at H, I, J, K, L, M and N in Fig. 2.

Fig. 5 indicates a welding of the tubular connection 84 to the lower end of the outer tube 72 and the welding of 15 the upper end of the latter around the inner tube 70 at 100.

Fig. 1 indicates that the lower parts of the interiormost 20 soot blower structures such as 66 and 68 are of an outside diameter less than the upper parts of these structures. The upper parts of these structures include external tubes 94 which are 4" in diameter and the vaporizable fluid flows in an annular passage 104 between each of these external tubes and the internal tube 98 for the soot blowing fluid. These tubes 98, like the tubes 70 previously described, are connected to a source of soot blowing fluid of a temperature of the same order as the temperature of the vaporizable fluid in the annular passage 104 in order that stresses arising from temperature gradients may be minimized.

The upper parts of the inner soot blower structures are 30 constructed in the manner above described, but the lower parts are of somewhat different construction. These lower parts include the outer tubes 108 which are of a diameter of 2". They are welded as at 110 (Fig. 9) to the outer tubes 94. However, before this welding takes 35 place the inner tubes 112 having radially positioned soot blower jet elements 116 welded thereto as indicated at 114. Like the elements 78 these elements 116 may be welded to the tubes 112 as solid rod portions of such radial extent that the inner tube with all of the elements 40 116 welded to it may be slidably moved into position within the outer tube 108. The elements 116 are disposed in successive groups along the length of the tubes 108 and 112, one of such groups being indicated at 118, the various elements 116 being aligned with openings in the 45 outer tube 108.

After the elements 116 have been welded to the tube 112, the latter is welded as indicated at 120 to the lower end of the inner tube 98. Thereafter, the outer tube 108 is slipped over the inner tube 112 and its projecting elements 116 so that the latter align with openings formed in the tube 108. Then these openings are filled with weld metal such as that indicated at 122. Thereafter, this weld metal and the elements 116 inwardly thereof are drilled to form the soot blower jet ducts, one of which is indicated at 124 in Fig. 10. These may be of a diameter of the order of 1/4". Each of the outer tubes 108 of the soot blower structures 66 and 68 is connected to a header 20 by a short tubular element 126, welded to the tube 108 as indicated at 130 in Fig. 9.

It will be noted from an examination of Fig. 1 that the 60 smaller diameter tubes 108 of the lower portions of the soot blower element 68 are mainly disposed beneath the baffle 18 which forms the roof of the high temperature furnace. Thus, these elements are subjected to temperatures much greater than the portions of the soot blower elements at higher levels, and to keep the tube metal of the elements 108 within allowable limits, the surface exposed to the gases is decreased, relative to the gases contacted surfaces of the upper parts of those soot blower structures. The illustrative arrangement of multiple 65 diameter soot blower structures also provides for the expansion of the fluid or fluid mixture within the annular parts of the soot blower structures, the percentage of steam or vapor increasing from the bottom of those structures, upwardly,

Although the invention has been described with reference to the details of a preferred embodiment, it is to be appreciated that the invention is not limited to all of these details. It is rather to be considered as of a scope commensurate with the scope of the subjoined claim.

What is claimed is:

In vapor generating apparatus, in a bank of upright vapor generating tubes, said tubes being horizontally spaced apart for the flow of heating gases therebetween, an upper pressure vessel chamber to which the upper ends of all the tubes are connected, a lower pressure vessel chamber having lower ends of all the tubes connected thereto, a soot blower tube disposed within one of the first mentioned tubes so as to leave an annular space exteriorly of the soot blower tube and within its enclosing tube, intermediately disposed soot blower jet structures welded to the soot blower tube and its enclosing tube and forming soot blowing jet passages leading from the interior of the soot blowing tube through its enclosing tube and directed toward the remainder of the first mentioned

tubes, and means for connecting the inlet of the soot blower tube with a source of soot blowing fluid, the soot blower tube having a part of reduced diameter at a position remote from its inlet.
